UNITED STATES PATENT OFFICE

GUSTAF IVAR BARCLAY, OF DETROIT, MICHIGAN, ASSIGNOR TO DETROIT STEEL PRODUCTS COMPANY, OF DETROIT, MICHIGAN, A CORPORATION OF MICHIGAN

WINDOW CONSTRUCTION

Application filed November 19, 1928. Serial No. 320,461.

The invention relates to a window construction and has for one of its objects to so construct a window that the sash may be secured in the window opening and the stool may then be inserted into the opening and beneath the sash. Another object is to provide a simple construction for holding the stool in place. A further object is to provide a simple construction for holding the sash in place relative to the wall sill. With these as well as other objects in view, the invention resides in the novel features of construction and combinations and arrangements of parts as more fully hereinafter set forth.

In the drawings:—

Figure 1 is a vertical section through the sill portion of a window construction, embodying my invention;

Figure 2 is a plan view thereof;

Figure 3 is a view similar to Figure 1, showing a modification;

Figure 4 is a cross section on the line 4—4 of Figure 3;

Figure 5 is a perspective view of a portion 25 of Figure 3;

Figures 6 and 7 are views similar to Figure 3, showing modification.

The invention is particularly applicable to all metal window constructions and as shown 30 the wall has at the lower end of its window opening 1 the stone and brick or tile sill portions 2 and 3, respectively. The window sash, which is preferably of metal, is set into the window opening and has the lower bar 4, which is provided with the downwardly opening 35 channel 5. 6 is one of a pair of anchoring clips, preferably formed of sheet metal, for the sash having at one end the upwardly extending flange portion 7 engaging in the 40 downwardly opening channel and secured to the lower bar by means of the screw 8 and at the other end the depending tongue 9, which extends between the stone and brick or tile sill portions 2 and 3, respectively, and is 45 securely anchored therebetween.

10 is the window stool which forms part of the frame work, this stool being preferably formed of sheet metal and extending within the window opening and beneath the inner 50 portion of the lower sash bar 4. This stool

has at its inner edge the depending portion 11, which terminates in the downwardly and outwardly inclined portion 12 at the inner side of the brick or tile sill portion of the wall. To take care of variations in the thickness of the wall and more particularly of the brick or tile sill portion sufficient clearance is provided between the outer edge of the stool and the upwardly extending flange portion 7 of the anchoring clip to permit the stool being moved relative to the lower sash bar.

13 is a finishing strip preferably formed of metal. This strip is adapted to extend beneath the lower sash bar 4 and is adjustably secured to the stool 10 as by means of the 60 rivets 14, which extend through the slots 15 extending transversely of the stool, the purpose of the adjustment being to provide for the adjustment of the stool relative to the 65 lower sash bar.

For holding the stool in place, I have provided the anchoring clips 16, which are spaced longitudinally of the stool and are adapted to be secured to the inner side of the brick or tile sill portion 3. Each of these 75 clips has an upper portion 17 which is upwardly and inwardly inclined at an angle corresponding to the portion 12 of the stool and which is adapted to be secured thereto as by means of the rivet 18.

In assembling, the window sash may be secured in the window opening, after which the stool with the finishing strip and its anchoring clips may be secured in place, this stool being inserted into the window opening 80 and its outer edge being passed beneath the lower sash bar. Then the plaster may be placed upon the sides of the window opening and upon the inner side of the wall.

In the modification shown in Figures 3, 4 and 5, provision is made for placing the heating radiator beneath the stool, this radiator 19 being located within a recess in the portion of the wall, part of the brick or tile sill portion being removed. In this modification the anchoring clips for the lower sash bar 20 are each formed with an upwardly extending flange portion 21 arranged within the downwardly opening channel of the lower sash bar. Furthermore, each clip is pro- 100

vided with the longitudinally spaced depending tongues 22 and 23 which together are adapted to embrace a part of the stone sill member 24, the tongue 22 being at the outer edge and the tongue 23 being at the inner edge and adjacent to the brick or tile sill portion 25. Each of these anchoring clips is further provided with the lateral tongue 26 which extends over the brick or tile sill portion and is adjustably secured to the support 27 for engaging the radiator hangers 28. The arrangement of the window stool 29 and the finishing strip 30 is very similar to that of the window stool 10 and the finishing strip 13, the stool anchoring clips 31 being located beyond the ends of the recess in the wall for receiving the radiator. This stool, however, is provided with the grill portion 32 above the radiator to provide for heat radiation.

20 In the modification shown in Figure 6, the arrangement of parts is very similar to that shown in Figures 1 and 2, with the exception that the wall sill and more particularly the brick or tile sill portion is formed with the 25 air duct 33 and the stool 34 is formed with the grill portion 35 above the air duct providing for the escape of air from this duct.

The modification shown in Figure 7 is very similar to that shown in Figure 6, the 30 grill portion 36 being formed of a separate sheet metal plate, which is secured to the stool.

What I claim as my invention is:

1. The combination with a wall having a 35 window opening and a window sash in the opening, of a stool separate from said sash and extending into the opening beneath the sash, and an anchoring clip secured to the wall at the inner side thereof and having 40 a portion for holding the stool from upward movement at its inner edge.

2. The combination with a wall having a window opening, of a stool extending into the opening, and an anchoring clip secured to the 45 wall at the inner side thereof and having a portion for holding the stool from upward movement at its inner edge.

3. The combination with a wall having a window opening and a window sash in the 50 opening, of a stool extending within the opening and beneath the sash, and a finish strip between the sash and stool and extending beneath the sash.

4. The combination with a wall having a 55 window opening and a sill member at the lower end of the opening and a window sash in the opening having a lower bar with a downwardly opening channel, of means for holding the sash in place, including a clip 60 having a portion engaging within the downwardly opening channel and longitudinally spaced depending anchoring portions embracing a portion of the sill.

5. The combination with a wall having a 65 window opening and a sill member at the

lower end of the opening and a window sash in the opening having a lower bar with a downwardly opening channel, of means for securing the sash in place including a clip having an upwardly extending portion within the downwardly opening channel, and longitudinally spaced depending tongues 70 embracing the sill member.

6. The combination with a wall having a window opening and a window sash in the 75 opening, of a stool extending into the opening and beneath the sash and provided with a grill portion intermediate its inner and outer edges, and an anchoring clip at the inner side of the wall having a portion engaging the stool at its inner edge to hold the same from upward movement.

7. The combination with a wall having a window opening and a frame member in the 80 opening, of a stool separate from said frame member and extending into the opening with one of its edges beneath said frame member, an anchoring clip carried by the wall, and means engaging said clip and the opposite edge of the stool for holding the same against 85 displacement.

8. The combination with a wall having a window opening and a frame member in the opening, of a stool extending into the opening beneath the frame member and provided with a grill portion, and an anchoring clip at the inner side of the wall having a portion engaging the stool at the inner edge thereof to hold the same from upward movement.

9. The combination with a wall having a 100 window opening and a sill member at the lower end of the opening and a window sash in the opening having a lower bar, of means for holding the sash in place, including a clip having a portion engaging said bar and longitudinally spaced depending anchoring portions 105 embracing a portion of the sill.

10. The combination with a wall having a window opening and a window sash in the opening, of a stool separate from said sash and extending into the opening beneath the sash, and an anchoring clip secured to the wall at the inner side thereof and having a portion fixedly connected to the inner edge 110 of the stool for preventing displacement 115 thereof.

11. The combination with a wall having a window opening and a window frame in the opening, of a stool extending into the opening beneath said frame and having a depending flange at its inner edge, and an anchoring clip secured to the wall at the inner side thereof and having a portion fixedly connected to said flange for preventing displacement 120 of said stool.

In testimony whereof I affix my signature.

GUSTAF IVAR BARCLAY.
